PUSH-BUTTON CONTROL DEVICE

Robert Demeulenaere and Marcel Demeulenaere,
New York, N. Y.

Application September 22, 1944, Serial No. 555,360

15 Claims. (Cl. 74—10.33)

1

This invention relates to a push button control and has for its object to provide a device of this character, particularly designed for application to the tuning shaft of a radio receiving set which permits adjustment of the individual push buttons with such high degree of exactness as to assure setting of the tuning device with the utmost precision.

A further object of the invention is the provision of a push button control device embodying simple structural characteristics enabling swift and convenient adjustment of the parts such as is necessary to enable the user to make desired changes in station selections.

Other objects and advantages of the invention will appear hereinafter in the detailed description and be particularly pointed out in the appended claims.

In the drawings, illustrating a preferred embodiment of the invention:

Figure 1 is a plan view of the device, and

Figure 2 is a vertical sectional view taken along the lines 2—2 of Figure 1.

Referring to the drawing in detail, a supporting frame 5 of suitable size and shape to be accommodated within the cabinet or casing of a radio receiving set is provided with front and rear walls 6 and 7, respectively, and an intermediate wall 8. Shafts 9 arranged in a horizontal row are mounted for combined axial sliding and rotatable movement in the walls 6 and 8, and the front ends thereof are so shaped and located as to constitute push buttons conveniently acceptable for button controlled tuning operations.

Each push button shaft 9 is formed at its rear end with a longitudinal bore 10 of substantial length which is screw threaded to engage an adjusting screw 11 fitted therein. The screws 11 terminate in the space between the walls 7 and 8 and are provided with head members 12 preferably of U-shape and with guides 13 whereby the screws are prevented from turning.

Each push button shaft 9 and its related screw 11 and head member 12 constitute an actuator and as many of these are provided as may be required to effect the number of variable adjustments needed to tune the radio set to the desired number of broadcasting stations.

Springs 14 connecting the head members 12 with the frame 5 normally retain the actuators 9—11—12 in forwardly projected inoperative position and each actuator is locked in the depressed operated position by a pawl 15 pivoted at

15a and engageable in a detent 16 formed in the button shaft 9. The pawl 15 is of such length as

2

to be common to all of the push button shafts 9 and each of the latter is additionally provided with a cam groove 17 in which the pawl is engaged when the shafts are in forwardly projected inoperative position. The detents 16 and cam grooves 17 are of annular form thereby insuring operative engagement with the pawl 15 regardless of the angular positions of the shafts 9.

The shaft 18 of the tuning device of the radio 10 (not shown) is keyed to a pinion 19 meshing with a gear segment 20 fixed to a shaft 21 rotatably mounted in the side members 22 of the frame 5. The shaft 21 is provided with crank arms 23 supporting a crank pin 24 which extends transversely 15 across the frame 5 behind the several head members 12 so that when anyone of the actuators 9—11—12 is pressed rearwardly against the tension of the related spring 14 the head member 12 engaging the pin 24 oscillates the shaft 21 20 and the motion thereof is transmitted to the tuning shaft 18 through the gear segment 20 and pinion 19.

The spring 25 connected with the tuning shaft 25 normally tends to turn the latter in a clockwise direction, and this force acting through the pinion 19 and segment 20 normally maintains the crank pin in engagement with the head members 12 thereby taking up whatever slack may exist in the motion between the parts as the result of imperfections in the manufacture thereof.

As usual in such devices, the radio set is conditioned for the reception of the selected radio transmitted station by predetermined angular adjustment of the tuning shaft 18 and to afford 35 an illustrative example it is assumed that, to accommodate the range of adjustment of the tuning shaft 18, it is turned through an angle of approximately 180°. Accordingly, the maximum movement imparted to the crank pin 24 by the actuators 9—11—12 is through an angle such that one-half of a revolution is imparted to the tuning shaft 18 through the segment 20 and pinion 19.

To enable the actuators when pressed to set 45 the tuning shaft in the proper positions to accurately tune in the predetermined broadcast stations, each actuator is associated with an adjusting device consisting of an adjusting shaft 26 and gears 28 and 29 for transmitting rotary motion to the related button shaft 9 whereby 50 through the action of the screw threads the position of the screw 11 is varied with respect to the shaft 9.

Each adjusting shaft 26 is rotatably and axially 55 movable in the walls 6 and 8 and is normally held

in forward inoperative position by a spring 30, the forward movement being limited by a gear 27 rigidly secured to the adjusting shaft and engageable with the rear face of the wall 6. In its forward position the adjusting shaft is locked in adjusted angular position by a pin 31 on the wall 6 engaging between the teeth of the gear 27.

The gear 29 is rigidly fixed to the button shaft 9 and the teeth of the gear 28 extend longitudinally of the adjusting shaft a distance sufficient to permit full stroke of the shaft 9 while maintaining the gears 28 and 29 in mesh. In this manner the pin 31 serves not only to lock the adjusting shaft 26 in adjusted position, but following adjustment of the actuator 9-11-12 the pin 31 also acts to lock it in set position.

From the foregoing it is apparent that the crank pin 24 may be moved a distance corresponding with the desired adjustment of the tuning shaft 18 to tune in the selected broadcast station by manipulation of the proper actuator 9-11-12 which has been previously adjusted for that purpose. To improve the precision of adjustment of the device the thread of the screw 11 and bore 10 are preferably of small pitch, and in addition the ratio of the gear wheels 28 and 29 is so selected that the push button shaft 9 is rotated at a reduced speed with respect to the adjusting shaft 26. By virtue of these mechanical expedients the screws 11 may be adjusted with the utmost precision with respect to the push button shafts 9, and in consequence a high degree of accuracy in tuning the device connected with the shaft 18 is afforded. Furthermore, the provision of the pin 31 and its association with the teeth of a gear wheel 27 of relatively large diameter enables the push button device to be locked in the precisely adjusted position.

Assuming that one of the actuators 9-11-12 has been operated to adjust the tuning shaft 18 to a desired broadcast station, the push button shaft 9 is locked by engagement of the pawl 15 with the detent 16, the gear wheel 29 sliding along the teeth of the gear wheel 28 during actual movement of the shaft 9. In case it may be desired to readjust the receiving set for the reception of a station broadcasting at a different wavelength, the related push button shaft 9 is operated and in so doing the pawl 15 is locked by the camming action of the groove 17, thereby disengaging the pawl from the detent 16 of the operative push button shaft 9, which latter, together with the screw 11 and head member 12 are instantly returned to inoperative position under the influence of the spring 14. Inward movement of the newly selected push button shaft 9 is continued until the pawl 15 engages in the detent 16 thereof in which position the crank arm 24 is set to adjust the tuning shaft 18 to the selected station. The crank pin 24 is caused to follow the forward movements of the head members 12 under the tension of the spring 25 and the latter serves additionally to take up whatever lost motion may exist between the parts and thereby avoid such errors in adjustment as might result from such lost motion.

What we claim is:

1. A device for turning a shaft through a predetermined angle comprising two actuator members movable as a unit to impart movement to said shaft and relatively adjustable to vary the amplitude of said movement, and means rotatable about an axis displaced from the actuator members and operably connected with one of said members for displacing said member with respect

to the other member to vary the relative adjustment of said members.

2. A device for turning a shaft through a predetermined angle comprising two actuator members 5 movable as a unit to impart movement to said shaft and relatively adjustable to vary the amplitude of said movement, means for displacing one of said actuator members with respect to the other to vary the relative adjustment of said members, and means to lock said displacing means in adjusted position.

3. A device for turning a shaft through a predetermined angle comprising two actuator members movable as a unit to impart movement to said shaft and relatively adjustable to vary the amplitude of said movement, releasable means normally effective to lock said actuator members in adjusted relative position and operable upon release to displace one of said actuator members 20 with respect to the other to vary the relative adjustment of said members, and means normally locking the releasable means in actuator member locking position.

4. A device for turning a shaft through a predetermined angle comprising two actuator members 25 movable as a unit to impart movement to said shaft and relatively adjustable to vary the amplitude of said movement, a rotatable member, and a speed reducing transmission gear connecting said rotatable member with one of said actuator members for displacing said actuating member with respect to the other actuating member to vary the relative adjustment of said actuator members.

5. A device for turning a shaft through a predetermined angle comprising two actuator members 30 movable as a unit to impart movement to said shaft and relatively adjustable to vary the amplitude of said movement, a rotatable member, a speed reducing transmission gear connecting said rotatable member with one of said actuator members for displacing said actuating member with respect to the other actuating member to vary the relative adjustment of said actuator members, and means to lock said members in adjusted relative position.

6. A device for turning a shaft through a predetermined angle comprising two actuator members 35 movable as a unit to impart movement to said shaft and relatively adjustable to vary the amplitude of said movement, a rotatable member, and a speed reducing transmission gear connecting said rotatable member with one of said actuator members for displacing said actuating member with respect to the other actuating member to vary the relative adjustment of said actuator members, and a crank arm movable within fixed limits and engaged and operable by said actuator members.

7. A device for turning a shaft through a predetermined angle comprising two actuator members having screw threaded connections with each other, said members being movable as a unit to impart movement to said shaft and being relatively adjustable by means of said threaded connection to vary the amplitude of said movement, means for variably turning the screw threads of one of said members with relation to the screw threads of the other member to vary the relative adjustment of said members, and a normally effective locking device for retaining said actuator members in relatively adjusted position and reliable incident to operation of said turning means.

8. A device for turning a shaft through a pre-

determined angle comprising two actuator members having screw threaded connections with each other, said members being movable as a unit to impart movement to said shaft and being relatively adjustable by means of said threaded connection to vary the amplitude of said movement, releasable means normally effective to lock said actuator members in adjusted relative position and operable upon release to variably turn the screw threads of one of said members with relation to the screw threads of the other member to vary the relative adjustment of said members, and means normally locking the releasable means in actuator member-locking position.

9. A device for turning a shaft through a predetermined angle comprising two actuator members having screw threaded connections with each other, said members being movable as a unit to impart movement to said shaft and being relatively adjustable by means of said threaded connection to vary the amplitude of said movement, a rotatable member, and a speed reducing transmission gear connecting said rotatable member with one of said actuator members for variably turning the screw threads of one of said actuator members with relation to the screw threads of the other actuator member to vary the relative adjustment of said actuator members.

10. A device for turning a shaft through a predetermined angle comprising two actuator members having screw threaded connections with each other, said members being movable as a unit to impart movement to said shaft and being relatively adjustable by means of said threaded connection to vary the amplitude of said movement, a rotatable member, a speed reducing transmission gear connecting said rotatable member with one of said actuator members for variably turning the screw threads of one of said actuator members with relation to the screw threads of the other actuator member to vary the relative adjustment of said actuator members, and means co-acting with said rotatable member for locking said actuator members in adjusted position.

11. A device for turning a shaft through a predetermined angle comprising two actuator members having screw threaded connections with each other, said members being movable as a unit to impart movement to said shaft and being relatively adjustable by means of said threaded connection to vary the amplitude of said movement, a rotatable adjusting shaft, means for locking said shaft in adjusted angular position, intermeshing gear wheels connecting said shaft with one of said actuator members for variably turning the screw threads of said actuator member with relation to the screw threads of the other actuator member to vary the relative adjustment of said actuator members, said gear wheels remaining in mesh throughout the range of unitary

movement of said actuator members whereby said locking means is effective to lock the first mentioned actuator member in adjusted angular position.

5 12. In a device for turning a shaft through a predetermined angle, an axially movable actuator adjustable in length and including relatively displaceable parts, a member movable by and in degree proportionally to the length of said actuator, 10 and a member rotatable about an axis located externally of said actuator operable to variably displace said parts for varying the length of the latter.

13. In a device for turning a shaft through a 15 predetermined angle, an axially movable actuator adjustable in length and including relatively displaceable parts, a member movable by and in degree proportionally to the length of said actuator, a member rotatable about an axis located externally of said actuator operable to variably displace said parts for varying the length of the actuator, and means to lock said rotatable member and said actuator in adjusted position.

14. In a device for turning a shaft through a 20 predetermined angle, actuatable members having screw threaded connection with each other and movable as a unit to impart movement to said shaft, one of said members being rotatable relatively to the other member to vary the adjustment of the screw threaded connection, means for imparting rotary movement to said rotatable member, and an annular detent on said rotatable member, and a pawl engageable in said detent.

15. In a device for turning a shaft through 25 a predetermined angle, actuatable members having screw threaded connection with each other and movable as a unit to impart movement to said shaft, one of said members being rotatable relatively to the other member to vary the adjustment of the screw threaded connection, means for imparting rotary movement to said rotatable member, and an annular detent on said rotatable member, a pawl engageable in said detent, and an annular pawl operating cam on said 30 rotatable member.
